DESIGN FOR A COMBINED BOTTLE AND CAP THEREFOR

Joseph Revson, New York, N. Y.

Application February 11, 1936, Serial No. 61,087

Term of patent 7 years

To all whom it may concern:

Be it known that I, Joseph Revson, a citizen of the United States, residing in New York, county and State of New York, have invented a new, original, and ornamental Design for a Combined Bottle and Cap Therefor, of which the following is a specification, reference being had to the accompanying drawing, forming part thereof.

Fig. 1 is a view in side elevation of a combined bottle and cap therefor showing my new design; and

Fig. 2 is a top plan view thereof.

I claim:

The ornamental design for a combined bottle and cap therefor as shown.

JOSEPH REVSON.
